**CARRIER FOR FRUIT OR SIMILAR ARTICLES OF
SUBSTANTIALLY SPHERICAL SHAPE**

Oscar L. Vines, New York, N. Y.

Application February 21, 1952, Serial No. 18,613

Term of patent 14 years

(Cl. D58—5)

FIG. 1**FIG. 2***To all whom it may concern:*

Be it known that I, Oscar L. Vines, a citizen of the United States, residing at city, county, and State of New York, have invented a new, original, and ornamental Design for a Carrier for Fruit or Similar Articles of Substantially Spherical Shape, of which the following is a specification, reference being had to the accompanying drawing, forming a part thereof.

Fig. 1 is a view in front elevation of a carrier for fruit or similar articles of substantially spherical shape showing my new design.

Fig. 2 is a view in side elevation thereof.

The rear view of the carrier is the same as the front view shown.

I claim:

The ornamental design for a carrier for fruit or similar articles of substantially spherical shape, as shown
